Application September 8, 1953, Serial No. 379,029

Claims priority, application Germany September 9, 1952

3 Claims. (Cl. 93—62)

The present invention relates to envelopes and more particularly concerns a method of and a machine for making envelopes of the five-seal or the like shape or size according to which selectively either the respective uppermost or the respective lowermost sheet of a stack of sheets is withdrawn with or without simultaneous formation of a fold. This method as heretofore practiced has the drawback that a spacing between the smallest and largest size to be worked is unavoidable so that the output per time unit is relatively limited. Moreover the heretofore known method does not make it possible to work the envelopes in such close succession that there is practically an uninterrupted track of closely succeeding envelopes passing by the respective treatment stations.

It is, therefore, an object of this invention to provide a method of and machine for making envelopes which will overcome the above mentioned drawbacks.

Numerous and various methods have been applied heretofore for making envelopes with gummed closure flaps. In this connection, there are used machines which work from a sheet, and there are also machines which work from a roll. With regard to the folding and pasting of the letter envelopes it may be mentioned that with the said two types of machines, the said working steps are carried out after the paper has been cut into blanks of predetermined size. With both manufacturing methods it is known prior, as well as after the folding step, to provide the blanks with adhesive or the like for the later pasting of the closure flaps. In order to dry said gummed closure flaps, it was heretofore necessary to employ a rather long drying path; in particular with high speed machines having high output, it was necessary in view of the high paper speed to increase the drying path more and more. This in turn required larger and larger designs of the drying devices in the shape of conveyor belts or conveyor chains. On the other hand, with these long drying paths especially when using conveyor belts, shifting of the work pieces frequently occurred which harmfully affected the folding process.

It is, therefore, another object of this invention to provide a method of and machine for making envelopes with gummed closure flaps which will reduce to a minimum the drying period for the adhesive applied to the paper surface so that, even with a maximum output and a maximum paper speed, only a very short drying path will be required.

It is still another object of this invention to provide a method of and machine for making envelopes from pre-cut sheets of paper which, while being rather simple, is highly economical, efficient and easily to be realized.

These and other objects and advantages of the invention will appear more clearly from the following specification in connection with the accompanying drawings in which:

Fig. 1 diagrammatically illustrates the principle of a first method according to the invention.

Fig. 2 diagrammatically illustrates a method which is somewhat modified over that of Fig. 1.

2

Fig. 3 is a diagrammatic illustration of a machine according to the invention, for carrying out the method according to Fig. 1.

Fig. 4 is a view taken along the line IV—IV of Fig. 3.

Fig. 5 illustrates the gumming of the bottom flaps.

Fig. 6 is a partial section through Fig. 3 taken along the line VI—VI thereof.

Fig. 7 is a diagrammatic illustration of a machine somewhat modified over that of Fig. 3 for carrying out the method according to Fig. 2.

Fig. 8 is a plan view of the side flap folding devices.

General arrangement

The essence of the invention consists in that the blanks cut to a predetermined size and withdrawn from a stack of blanks are passed by the treatment stations in an overlapping or fanned out manner. These blanks or work pieces, while being in the said arrangement, have, according to the new method, applied the adhesive or gum for the later pasting of the closure flaps, whereupon after effected drying, the folding, turning over and gumming of the flaps extending transverse to and in the conveying direction, is effected in such a manner that an uninterrupted paper train is formed, the work pieces of which subsequently by the turning-over step and closing of the closure flaps are separated into individual finished work pieces.

The employment of the method, according to the present invention, i. e. the arrangement of a staggered paper layer according to mass production methods for purposes of folding and pasting has considerable advantages over the heretofore known methods. According to the present invention, depending on the width of the staggering, simultaneously a more or less great number of work pieces can be subjected to the folding and gumming process. With reference to the length of the blanks in the conveying direction, according to the present invention, the heretofore customary inter-spaces between the smallest and largest sizes to be worked, are completely eliminated since the work pieces are subjected to the folding step in an uninterrupted sequence. This results in a considerable increase of the output without increasing and accelerating the working tools while the paper blanks may move at a minimum speed. According to the present invention, a conveyor is provided for conveying the work pieces which conveyor has its outer surfaces provided with an elastic adhesion-creating mass. As support for said conveyor, a slide rail or guiding rail may be provided which presses the work pieces carried by said conveyor against the latter so that the work pieces will be passed through the machine in a safe manner without changing their position relative to said conveyor.

The present invention furthermore comprises a method of depositing and drying the paste or gum on the closure flaps. According to this new method, the paper sheets to be provided with paste or gum at the various closure flaps, are prior to the application of such paste or gum, dried in any convenient manner so that the humidity contained in the paper sheets will be evaporated. This method makes it possible that immediately following the evaporation process, paste or gum can be applied to said paper sheets and said paste or gum will immediately harden on the paper surface and due to the heat radiation of the heated paper will immediately and completely dry. The advance in the art as brought about by the present invention consists in that, even with a maximum output and at a maximum paper speed, only a very short drying path will be required for the drying period.

Structural arrangement

Referring now to the drawings and Figs. 1 and 3 thereof in particular, the respective lowermost sheet or blank

is by means of suction rollers 2, 3 withdrawn from the stack of blanks 1 while simultaneously with the withdrawal of such blank a fold is formed—folding over of the closure flap. The small development of the suction rollers 2, 3 cause the respective sheet or blank to be pulled out below the stack of blanks only to a small extent so that there will be formed a layer or train of echeloned or overlapping blanks 4 as has been clearly shown in Fig. 1. According to the present invention, when the withdrawal is effected, first the closure flap 5 is folded over so that the latter will rest on what will later form the address side of the envelope. The thus staggered blanks overlapping each other and provided with a turned over closure flap are successively passed upon a pair of belts or bands 6, 7 (see Figs. 3 and 6). The said belts or bands carried by pulleys 31, 32 carry the echeloned or overlapping work pieces 4 in cooperation with the guiding rails 8, 9 during the gumming and drying process. Between said conveyor belts or bands 6, 7 (Figs. 3 and 6), there is provided a heating chamber 10 in which are arranged heating tubes 11. When the train of overlapping work pieces 4, by means of the conveyor belts 6, 7, is passed over the heating chamber 10, the said echeloned or overlapping work pieces are, according to the present invention, heated to such an extent that the gum or paste 12 subsequently applied to said work pieces by a gumming device 13 will immediately harden on the paper surface and will, due to the heat radiation of the train of work pieces itself, completely dry. On its further way over the heating chamber 10, the work pieces 4 are passed onto the conveyor belt 14. The conveyor belt 14 is, according to the present invention, designed similar to the conveyor belts 6, 7 and has its outer surface provided with an elastic adhesion-creating mass as, for instance, rough rubber, sponge rubber or cellulose sponge. When the work pieces 4 enter between the conveyor belt 14 and the guiding rail 15, the work pieces are by means of the guiding rail 15 pressed against the conveyor belt 14 and are carried through the machine while the work pieces slide along said guiding rail 15. Laterally of the conveyor belt 14, there are arranged folding knives 16 and folding loops 17. While the train or overlapping work pieces 4 is passed through the folding knives 16 and folding loops 17, those two flap portions 18 of each work piece 4 which stick out from the central portion of the work piece in a direction transverse to the conveying direction, are folded over so that an uninterrupted train is formed made up of the individual work pieces each of which has already three folds. When the train of work pieces leaves the conveyor belt 14 and the guiding rail 15, it enters between the delivery rollers 19, 20. On the upper roller 20 there are provided gum or paste-applying means which receive the paste or gum from a device 21 arranged thereabove for pasting the bottom flap 24.

As soon as the leading folding edge 22 passes below the contact point of the two delivery rollers 19, 20, the respective leading work piece 25 is at an increased speed separated from the entering train of work pieces because the rollers 19, 20 have a higher speed than the belt 14. Simultaneously the work piece is provided with the paste or gum 23 for pasting the bottom flap 24. The two delivery rollers 19, 20 feed the work piece 25 provided with three folds into the folding pocket 26 so that while the direction of movement is being reversed, the bottom flap 24 is folded over and is pasted to the two lateral flaps 18. When the work piece passes through the rollers 19, 20, the closure flap 5 which was folded over during the withdrawal of the respective sheet from the pile of sheets 1, is caught by the suction roller 27, is opened and is passed between the rollers 27 and 28. The roller 27 feeds the now leading closure flap 5 through guiding means 30 while the work piece is caught by the lower suction roller 28 directly behind the folding edge 29 and by the guide 30 is started up while the closure flap 5 is being closed.

According to the method illustrated in Fig. 2, the with-

drawal and folding of the work pieces is effected in a manner similar to that of the method according to Fig. 1. Therefore, the same reference numerals as in Fig. 1 have been employed in Fig. 7 illustrating the machine for carrying out the method of Fig. 2. However, the reference numerals employed in Fig. 7 and designating parts corresponding to those of Fig. 3 are provided with the same reference numerals as employed in Fig. 3 with the addition of the suffix "a." As will be seen from Figs. 2 and 7, the method and arrangement respectively illustrated therein differ from that of Figs. 1 and 3 in that the paste or gum is applied to the closure flaps subsequent to the folding step. According to Figs. 2 and 7, an envelope is made by subjecting the blanks directly to the folding process while the work pieces, when they are withdrawn from the stack 1a, are simultaneously staggered or fanned out. The preliminary breaking, the folding over and the gumming is carried out in the same succession as referred to in Fig. 1. The thus-formed train is then divided up into individual pieces in such a manner that the individual work pieces are staggered with regard to each other in an overlapping manner and in this position are conveyed together.

The thus-formed paper track is, according to the present invention, heated by any convenient means such as the heating drum 10a (Fig. 7) whereupon the paste or gum is applied to the closure flaps. After the drying process has been completed, the closure flaps are closed while the work pieces are collected and stacked up to a stack.

As far as the principle of the invention is concerned, it is immaterial whether the pre-cut sheets or blanks are withdrawn from the stack of sheets with or without the simultaneous formation of a fold. The invention may also be applied where the withdrawal of the sheets is effected with open unfolded sheets.

It is furthermore to be understood that the present invention is, by no means, limited to the particular methods and devices described in the preceding specification with regard to the accompanying drawings, but also comprises any modifications within the scope of the appended claims.

What I claim is:

1. A method of making envelopes from sheets arranged in a stack and cut to size with corner portions thereof cut to respectively form the side, bottom and closure flaps, which includes the steps of: withdrawing from said stack in a continuous process one sheet after another while advancing said sheets in superimposed but staggered position so that said sheets overlap each other in the direction of advancement of said sheets; heating said sheets while they are thus being advanced; applying adhesive to that portion of said heated sheets which will form the closure flap; drying the thus applied adhesive; subsequently folding at least those portions of said sheets which form the side flaps of the envelopes while simultaneously advancing the thus folded sheets in superimposed and overlapping condition; segregating the individual folded sheets from each other; applying adhesive to marginal portions of the side flaps of said segregated and folded sheets; folding over the bottom flaps of said segregated and folded sheets while pressing the same against said side flaps; and subsequently folding the closure flaps so that they will lie on the back side of the envelopes.

2. A method of making envelopes from sheets arranged in a stack and cut to size with corner portions thereof cut to respectively form the side, bottom and closure flaps, which includes the steps of: withdrawing from said stack in a continuous process one sheet after another while advancing said sheets in superimposed but staggered position so that said sheets overlap each other in the direction of advancement of said sheets while thus advancing said sheets folding at least those sheet portions which form the side flaps of the envelopes to be made; heating the thus-folded sheets; applying adhesive to that portion of said sheets which will form the closure flaps; drying

the thus-applied adhesive; applying additional adhesive to those portions of said sheets which will form the side and bottom portion of the envelopes; and pressing said side and bottom flaps against each other so as to connect the same together.

3. An arrangement for making envelopes, which includes a rotatable drum, heating means arranged within said drum for heating the same, first conveying means provided with elastic gripping means and arranged to convey in overlapped relationship pre-cut paper sheets to be made into envelopes over said drum over a pre-determined arc thereof for heating said sheets, means arranged adjacent the periphery of said drum intermediate the end points of said arc and a considerable distance away from the starting point of said arc for applying adhesive means to that portion of each sheet passing over said drum which will form the closure portion of the respective envelope, second conveying means adjacent said drum for receiving in overlapped relationship the sheets passed over said arc of said drum, folding means arranged adjacent to and laterally of said second conveying means for folding portions of said sheets while in said overlapped relationship into side flaps of the respective envelope, roller means arranged adjacent that

end of said second conveying means which is remote from said drum to receive the folded sheets from said second conveying means, said roller means having a rotational speed greater than the speed of said second conveying means to thereby segregate the individual folded sheets from each other, paste-applying means adjacent said roller means for applying paste to that portion of said sheets which will form the bottom flap of the respective envelope, and folding means for folding said bottom flap and fastening the same to said side flaps.
